SKATE CONSTRUCTION

Lee A. Woolley, Kokomo, Ind., assignor to Kings-
ton Products Corporation, Kokomo, Ind., a cor-
poration of Indiana

Application March 7, 1946, Serial No. 652,627

2 Claims. (Cl. 280—11.26)

1

The present invention relates to a skate construction, generally, and more particularly to means for positively locking a shoe plate to a skate frame in desired adjusted relationship.

Skates, as manufactured at the present time, which include shoe plates relatively adjustable with respect to the skate frames, are made with adjusting means comprising a square hole for a bolt in a plate and a longitudinal slot in the frame member, or vice versa, the bolt, having a square head or neck, which serves to prevent the bolt turning while nut is being tightened, is engaged through the hole and slot and the plate is fastened in adjusted position by turning up the nut to cause tight frictional engagement of the two parts. The slot margins are smooth. Experience has demonstrated that oftentimes such adjustment is not positive and easily loosens, as it depends solely on the friction of the clamping nut to maintain the adjustment, making it necessary for the skater to take time out to readjust the parts. Such described adjusting means have proved unsatisfactory.

The present invention has to do with a construction for securing a plate of a skate to the skate frame by means which positively engage the plate and frame to thereby eliminate looseness of a bolt from allowing relative displacement of the adjusted parts.

An object of the present invention is to provide an improved positive lock for securing a shoe plate to a skate frame in desired adjusted relationship.

Another object of the present invention is to provide means for positively locking together two relatively movable parts by a bolt having a square neck which neck enters a similarly shaped opening in one of said members and projects into a serrated slot in the other member, the square neck engaging opposed serrations to thereby hold said parts together against relative movement in the direction of the slot.

A further object of the present invention is to provide improved skate construction by providing means for securing a shoe plate to a skate frame in adjusted relationship in which interengageable means are employed to make the desired adjustment a positive one.

The above, other and further objects of the present invention will be apparent from the following description and accompanying drawing.

An embodiment of the present invention is illustrated in the accompanying drawing and the views thereof are as follows:

Figure 1 is a bottom plan view of a roller skate

constructed in accordance with the principles of the present invention;

Figure 2 is an enlarged fragmental transverse sectional view, exploded, taken in the plane of line II—II of Figure 1.

Figure 3 is a fragmental bottom plan view showing relationship of a plate and frame, a serrated frame slot and in section engagement of the square neck of a bolt with the slot margins to effect positive adjustment of the plate and frame; and

Figure 4 is bottom plan view of the front or sole plate.

As shown on the drawing:

The illustrated roller skate is constructed, in the main, of stampings and comprises a skate frame 5 having front legs 6 and rear legs 7 for supporting the front rollers 8 and rear rollers 9, respectively. The front rollers 8 are carried on a front axle 8a, while the rear rollers 9 are carried on a rear axle 9a, which axles pass through registering apertures in the legs.

10 designates a front or sole plate, while 11 designates a rear or heel plate.

15 The front end of the skate frame 5 is slotted at 12 which slot opens through the front end of the frame. A slot 13 opening through the rear end of the frame is shown, the latter slot being shown as shorter than the front slot 12.

20 There are two other slots formed in the frame body, the front intermediate slot 14 and the rear intermediate slot 15, these slots extend lengthwise of the frame and the side margins thereof are serrated as at 14a and 15a respectively.

25 Formed in the front or sole plate 10 is a square hole 18, while a similar square hole 19 (not shown) is formed in the rear or heel plate 11. These square holes are formed so that the diagonals thereof extend longitudinally and transversely of the length of the frame.

30 Near the front end of the front or sole plate 10 lugs 20 are struck therefrom, extending downwardly, with the ends bent outwardly away from each other for hooking engagement with the margins of the skate frame defining the front end slot 12.

35 In a similar manner lugs 21 are struck downwardly out of the rear or heel plate 11 with their ends outturned in opposed relationship for hooking engagement with the margins of the frame defining the rear end slot 13. The engagement of the lugs, just described, prevents relative turning movement of the plates with respect to the skate frame as the skate is being used by a wearer, for skating, even though the nuts be loose.

40 In order to secure the plates 10 and 11 to the

skate frame 5, in longitudinally adjusted relationship, bolts 22 are employed. Each bolt comprises a head 23, a square neck 24 and a threaded shank 25. For cooperating with the bolts there are provided wing nuts 26 and washers 27.

To adjust the front or sole plate 10, longitudinally of the skate frame 5, the plate is applied to the frame with the lugs 20 engaged in the front end slot 12, one of the bolts 22 is inserted through the square hole in the plate 10 and through the front intermediate slot 14. Because of the arrangement of the square hole in the plate, two opposite edges of the square neck 24 of the bolt will engage opposed serrations in the front intermediate slot 14 thereby positively securing the sole plate 10 in longitudinally adjusted relationship with respect to the skate frame 5. A washer 27 is thereupon applied over the bolt and a nut 26 screwed onto it tensioning the washer to thus firmly secure the sole plate in position.

The rear of heel plate 11 is attached in the same manner.

It will thus readily be seen that the employment of bolts having square necks makes positive adjustment connections between the plates and the skate frame. Such construction provides interengageable means for positively securing the parts in desired adjusted relationship.

Because of the positive engagement of the square necks of the bolts with the serrations in the slots and the square holes in the plates, it is unnecessary to rely on the tightness of the nuts for securing the plates in adjusted position with respect to the skate frame. It has been found that even when a nut is loose the parts retain their relatively adjusted relationship by reason of the positive engagement of the square neck of a bolt with the hole in the plate and the serrations in an intermediate slot.

The construction described is one which lends itself to economical manufacture and at the same time is one which is highly effective in use for accomplishing the purpose intended.

Shown as attached to the front or sole plate 10 are toe straps 28. A heel guard 29 is formed as a part of the rear or heel plate 11 and is provided with slots 30 for the reception of strap means to attach the heel portion of the skate to a foot of a wearer, in the usual manner.

It is to be understood that the neck of the bolt might be of a polygonal shape other than square, in which event the bolt receiving holes in the plate would be of corresponding shape to receive a bolt in relative non-rotative relation.

It will, of course, be understood that various details of construction may be varied through a wide range without departing from the principles of this invention and it is, therefore, not the purpose to limit the patent granted hereon other-

wise than necessitated by the scope of the appended claims.

I claim as my invention:

1. A skate construction including a skate frame having slots in its ends opening through the extremities of the ends and having two other intermediate slots lengthwise of the frame, the intermediate slots having serrated side margins with the serrations on opposite margins of a slot in register, a heel plate and a sole plate adapted for application to the frame, each plate having a square hole in it in its longitudinal axis and with its diagonals lengthwise and crosswise and also having depending lug means to enter said end slots and engage underneath the margins of the end slots, and bolts having square necks entered through the holes in said plates with opposite corners of the necks engaging serrations in the intermediate slots for holding the plates in adjusted relationship with respect to the frame, and nuts for securing the bolts in place.

2. In combination two relatively movable members, one of said members having two slots in it in endwise spaced relation with one of said slots opening through an end extremity of said one member, the side margins of the other of said slots being serrated, the other of said members having portions enterable only through the open end of said one slot for hooking engagement with said one member to prevent relative turning movement of said members and also having a square hole therein to overlie the said other slot of said one member, and means for locking said members in adjusted position comprising a bolt having a square neck entered in the hole of said other member and having two diagonally opposite corners of its neck engaging with said hole and also with a pair of opposed serrations in the other slot of said one member to thereby lock said two members together in endwise adjusted relation, and a nut on the bolt to tighten it in place in said two members to thereby retain said two members in adjusted position, the hooking engagement of said other member with said one slot of said one member preventing relative turning movement of said members when the nut is loose.
